UNITED STATES PATENT OFFICE.

MAX C. MILLER, OF CUMBERLAND HILL, RHODE ISLAND, ASSIGNOR TO JENCKES KNITTING MACHINE COMPANY, OF PAWTUCKET, RHODE ISLAND, A CORPORATION OF RHODE ISLAND.

KNITTING MACHINE.

Application filed April 5, 1921. Serial No. 458,640.

The invention relates to that class of circular knitting machines in which the needles are mounted in the needle cylinder and are operated by cams and pickers arranged about 5 the cylinder, the relative movements between the needle cylinder and needle operating cams and pickers requisite for knitting a tubular fabric provided at intervals with heel and toe pockets being produced by rotary and reciprocating movements of the needle cylinder.

The object of the invention is to improve and simplify the construction and arrangement of the various parts and mechanisms of a machine of this type and to that end the 15 invention comprises the features of construction and combination of parts hereinafter described and set forth in the claims.

The various features of the invention will be readily understood from an inspection of 20 the accompanying drawings and the following detailed description of the machine illustrated therein.

In the drawings Fig. 1 is a left side elevation of a machine embodying all of the various features of the invention in their preferred form, Fig. 2 is a similar elevation showing the upper part of the machine, Fig. 3 is a detailed elevation looking toward the right in Fig. 2, Fig. 4 is a right side elevation 30 of the upper part of the machine, Fig. 4^a is a perspective showing a part of the actuating mechanism for the yarn clamp and cutter, Fig. 5 is a vertical sectional elevation, Fig. 5^a is a detailed view showing one of the yarn changer fingers, Fig. 6 is a similar view on a larger scale, Fig. 7 is a plan view of the latch ring and yarn feeding and changing mechanism, Fig. 7^a is a perspective view of the yarn guide plate, Fig. 8 is a plan view 40 with the latch ring removed, Fig. 8^a is a sectional view of the parts carried by the pattern shaft, Fig. 9 is a sectional plan view with the bed plate removed, Fig. 10 is a detail plan view of the web holder cam ring, Fig. 11 is a 45 diagrammatic view showing a development of the cams and devices operating on the needle butts, Fig. 12 is a sectional plan view showing the mode of operation of the needle leveling mechanism, Fig. 13 is a sectional 50 view along line 13, Fig. 12, Fig. 14 is a vertical sectional view showing the motion changing mechanism through which the needle cylinder is rotated and reciprocated, Fig. 15 is a detailed sectional elevation showing the

mechanism for driving the fabric receiving 55 can and Fig. 16 is a detail showing a part of said mechanism.

The machine shown comprises in general a rotary needle cylinder carrying the usual long and short butt needles, a surrounding support or cam cylinder on which the needle operating cams and pickers are mounted, mechanism for rotating and reciprocating the needle cylinder, a series of yarn carrying fingers for delivering yarn to the needles and for changing the yarn during the knitting, mechanism for raising and lowering the needle cylinder to vary the length of stitch at different parts of the stocking, and an intermittently moving pattern mechanism 60 carrying the various cams for automatically operating and controlling the various parts and mechanisms of the machine. The machine is also provided with mechanism which may be utilized in knitting half hose to automatically level the needle after a half hose has been completed and then stop the machine 65 preparatory to the transfer of a ribbed top to the leveled needles.

The machine shown is provided with a rotary needle cylinder 1, in which latch needles 2 are mounted in the usual manner (Figs. 5 and 6). The needle cylinder is carried on and connected to rotate with a gear 3, which is mounted to rotate within a supporting ring 80 4. The supporting ring is provided with three spiral or worm ribs 5 which rest upon rolls 6 carried by vertically adjustable supports 7. The ribs are held firmly upon the supporting rolls by rolls 8 which are carried by vertically movable plungers 9 and are forced against the upper sides of the ribs by springs 10. The plungers are mounted in holes formed in the cam supporting plate 11 and the springs and plungers are retained in place by over-lying plates 12 which may be readily removed in assembling the machine or for replacement of springs or plungers. By rotation of the worm ring the needle cylinder may be raised and lowered to vary the 85 length or tightness of the stitch or to change the relation of the needles and web holders in transfer work. The ring is forced in a direction to lower the needle cylinder by a spring 13 (Fig. 9) and is moved in the opposite direction through a horizontal rod 14, the forward end of which engages an arm 15 depending from the ring, and the rear end of 90 100 105

which is engaged by an adjustable screw 16 carried in the lower end of a lever 17 (Fig. 4). The lever is mounted on a stud 17' and its upper end is provided with contact pieces 18 and 20 adapted to engage cams mounted on a disk 19 which is carried by the pattern shaft 21. These cams by engagement with one or the other of the contact pieces determine the height of the needle cylinder at various parts of the stocking, or during the leveling and transfer operations.

The needle cylinder is rotated and reciprocated through a gear 22 which engages the gear 3 and is secured upon the upper end of a short vertical shaft 23 (Figs. 4, 5, 9 and 14). The lower end of the shaft is connected through a beveled gear 24 with a beveled gear 25, which is formed on the end of a sleeve 26 loosely mounted on the driving shaft 27.

20 A motion changing clutch sleeve 28 is keyed to slide on the sleeve 26 and may be shifted to connect the sleeve 26, and therefore the needle cylinder, with either a continuously rotating pinion 29 or an oscillating pinion 30.

25 The rotary pinion 29 is pinned to the shaft 27 while the oscillating pinion 30 is loosely mounted on the sleeve 26. The oscillating pinion is driven through an oscillating segment 31 connected by a link 32 with a crank pin 33 on a gear 34, which meshes with the rotary pinion 29, the gear being four times the diameter of the pinion so that it makes one revolution for four revolutions of the driving shaft. The clutch sleeve 28 is provided at each end with a projecting clutch tooth, one of which is adapted to engage a recess in the side of pinion 30 and the other to engage a recess in the side of the pinion 29.

The mechanism for shifting the clutch to change the motion of the needle cylinder from rotary to reciprocating, or from reciprocating to rotary, comprises two cam rings 35 and 36 adjustably secured on opposite ends of the clutch sleeve and two radially movable pins 37 and 38. Each cam ring is provided with an inclined cam surface 39 adapted to engage the corresponding pin and to shift the clutch from one pinion to the other. The clutch shifting pins are automatically raised and lowered and are spring-pressed so that they will ride on the cam rings when free to do so. After the active pin has cooperated with the corresponding cam ring to shift the clutch it moves down inside the ring and acts to lock the clutch in shifted position. In Fig. 14 the pin 38 is in clutch-locking position and holds the clutch in engagement with the rotary pinion 39 while the pin 37 is raised and held in inactive position. When the motion is to be changed from rotary to oscillating the pin 38 is raised and the pin 37 is released so that it rides on the cam ring 35 until the inclined surface 39 on this ring engages the side of the pin and shifts the clutch to the right and into en-

gagement with the oscillating pinion 30. The incline 39 is so located that the clutch is shifted while the tooth on the end of the clutch is in register with the recess in the pinion 30 and the clutch is quickly and positively shifted from the rotary to the oscillating pinion. As the shifting of the clutch is completed the pin 37 moves down back of the ring 35 and locks the clutch in shifted position. When the motion is to be again changed from oscillating to rotary the pin 37 is raised and the pin 38 released so that the clutch is positively shifted in a similar manner by the engagement of the incline 39 on cam ring 36 with the pin 38 and is locked so by the pin as indicated in Fig. 14.

The clutch controlling pins 37 and 38 are alternately raised and lowered at proper intervals through two levers 40 and 41, mounted on the stud 17'. The forward ends of the levers underlie studs 42 projecting from the clutch pins and the rear ends are arranged to bear on cams 43 carried by the pattern cam drum. (Figs. 5 and 8.)

The driving shaft is driven through a belt passing over a pulley 44 secured to the outer end of the shaft. The machine may be stopped by shifting the belt from the driving pulley onto a loose pulley 45 and may be started by shifting the belt from the loose onto the driving pulley. The belt may be thus shifted by a belt shifter 46, which is forced in a direction to hold the belt on the loose pulley by a spring 47. The belt shifter may be moved to shift the belt onto the driving pulley and thus start the machine by a cam 48 secured to the inner end of a rock shaft 49, and arranged to act on a pin 50 projecting from the belt shifter. The rock shaft may be provided with a handle at its outer end through which it may be conveniently operated by the operator. When the belt shifter is thus moved it is locked in position by a latch arm 51 projecting forward from a lever 52 and arranged to engage a notch 53 in the belt shifter bar. The forward end of the latch arm projects within convenient reach of the operator and the latch arm is held yieldingly in engagement with the belt shifter bar by a spring 54. In knitting half hose the latch arm may be automatically raised to release the belt shifting bar and thus stop the machine by a cam 55 on the pattern drum, which is arranged to engage one end of a bell crank lever 56 (Fig. 4). The other end of the lever is provided with an inclined cam surface arranged to act on and depress the upper end of a rod 57, the lower end of which is connected with the rearwardly projecting arm of the latch arm lever 52.

The pattern shaft 21 is moved at proper intervals through a ratchet wheel 59 secured to the end of the shaft (Figs. 1 and 2). The ratchet wheel is provided with teeth which

are engaged at intervals by an actuating pawl 61 mounted on a pawl-carrying lever 62 and forced in a direction to engage the ratchet by a spring 63. The pawl is normally held 5 out of action by a latch 64 pivoted on the pawl-carrying lever and arranged to hook over a lug 65 on the side of the pawl. The latch is disengaged to render the pawl active at suitable intervals by a lever 66, one end of 10 which is arranged to overlie the tail of the latch and the other end of which is arranged in the path of a series of lugs 67 on a pattern chain 68. A spring 69 connects the latch and its controlling lever, and tends to hold the 15 latch in engagement with the lug 65 and to hold the lever in normal position with an arm 70 on the lever in engagement with a fixed stop 71. The teeth on the ratchet 59 are of different lengths and the engagement 20 of the actuating pawl with the proper tooth when the pawl is rendered active is insured by a guard 72, the position of which is automatically shifted to prevent engagement of the pawl with any but the proper tooth. The 25 guard is formed on the end of a lever which is pivoted at 73, and the position of the guard is controlled and determined by a cam 74 secured to the inner side of the ratchet wheel and engaged by a bearing piece 75 30 which is adjustably secured on the end of the guard lever. The lever is held in engagement with the cam by a spring 75' and the cam is so shaped that at each forward movement of the ratchet wheel the guard is properly positioned to insure the engagement of the pawl with the succeeding tooth when the 35 pawl is next rendered active. In order to insure the proper timed relation between the pattern chain and pattern shaft and to automatically restore the timed relation in case 40 it is unintentionally disturbed, as in hand manipulation of the machine, the cam 74 is provided at one point with an abnormally low part, as at 76, which will so position the 45 guard that engagement of the pawl with the tooth of the ratchet wheel next to be engaged will be prevented unless the guard is otherwise positioned to permit engagement of the tooth by the pawl. The guard is thus positioned 50 by a timing or re-timing mechanism, comprising a lever 77, the upper end of which is arranged to engage a pin 78 projecting from the guard lever, and the lower end of which is arranged at one side of the 55 lower end of the pawl releasing lever 66 and in the path of a single broad lug 67' on the pattern chain. If the chain and shaft are in proper time the low point 76 on the cam 74 is brought into register with the contact 60 piece on the guard lever by the engagement of the actuating pawl with the tooth corresponding to the lug 67 next preceding the broad lug 67' on the pattern chain. When 65 the pawl is to engage the next tooth the broad lug releases the pawl and at the same

time the broad lug actuates the lever 77 to so position the guard 72 that the pawl will engage the tooth and advance the pattern cam shaft 21. If for any reason the shaft and chain are out of time the shaft will be 70 advanced step by step by the pawl as it is released by the successive lugs 67 until the low point 76 on the cam 74 registers with the contact piece on the guard lever, after which there will be no advance of the shaft by the 75 pawl when released until the broad lug 67' is brought into active position and not only releases the pawl but also moves the guard into position to permit the pawl to engage the tooth of the ratchet wheel corresponding 80 to the lug 67' on the pattern chain.

The pawl-carrying lever 62 is actuated from a continuously rotating cam 79 secured to the end of a shaft 80, which is connected with the crank gear 34 for actuating the 85 oscillating segment of the mechanism for reciprocating the needle cylinder. The cam, therefore, makes one revolution and actuates the pawl during each complete oscillation of the segment or reciprocation of the 90 needle cylinder. The cam is engaged by a cam lever 81 which is connected by a link 82 with the pawl-carrying lever. A spring 83 connected with the pawl-carrying lever tends to retract the pawl and holds the cam lever 95 in engagement with the cam. Each time the pawl is retracted the end of the pawl rides against a fixed stud 84 arranged to swing the pawl about its pivot and maintain it in position for the re-engagement of the latch 100 64 with the lug 65.

Since the various changes controlled or dictated by the pattern mechanism should occur at varying points in the revolution or reciprocation of the needle cylinder the pawl-actuating cam 79 is preferably provided with a plurality of rises or steps properly distributed along the periphery of the cam to give to the pawl a series of short and rapid advance movements timed with relation to the movements of the needle cylinder to coincide with the points at which the changes dictated by the pattern mechanism should be effected. This multiple step advance movement of the pawl not only enables the changes 115 to be accurately timed without the necessity of extreme accuracy in the positioning of the controlling cams on the pattern drum, but also enables the cams to be more compactly arranged about the periphery of the drum 120 so that the diameter of the drum may be materially reduced. This feature, in connection with the variation in the lengths of the teeth of the ratchet wheel engaged by the pawl, enables the movements imparted to the pattern drum to be so selectively controlled as to reduce the idle movement of the drum and consequently enables the diameter of the 125 drum to be further reduced.

In making certain changes as, for instance,

in changing the yarns it may be desirable, under varying conditions, to vary the interval between two successive advance steps of the pattern drum pawl and means is therefore provided for varying the relative positions of successive rises on the cam 79. In the construction shown the pattern drum is advanced by the step on the cam indicated at 84 to insert a new yarn and after a short interval is again advanced by the step 85 to withdraw an active yarn. In order that the lap of the yarns may be varied the rise 84 is formed by a plate adjustably secured to the main cam 79 and movable thereon to vary the position of the rise 84 with relation to the rise 85.

The pattern chain is advanced a step, for each revolution of the shaft 80, and therefore a step for each four revolutions of the needle cylinder, by a cam 86 secured to the shaft 80 and engaging a pawl-carrying lever 87. A pawl 88 is pivoted on the lever and is held by a spring 89 in engagement with the teeth of a ratchet wheel 90 which is secured to the upper pattern chain sprocket wheel 91. A stop pawl 92 prevents reverse movement of the ratchet wheel.

The needle operating cams and pickers are mounted on the supporting plate 11, which is provided with a central cylinder 93 surrounding the needle cylinder (Figs. 5, 6 and 11). The upper edge of the cylinder forms a ledge 94 for underlying the needle butts and supporting the needles at the tuck level. The knitting cams comprise the stitch cams 95 and 96, the needle elevating or side cams 97 and 98, the lower center cam 99, and the upper center cam 100, which is formed on a guard plate 101 overlying the stitch and side cams. The needle depressing picker 102 is a double acting picker having oppositely projecting lips adapted to overlie and engage two adjacent needle butts. The picker is in the form of an arm pivoted to the upper end of a vertical post 103, which is mounted to swing in a bearing bracket 104 secured to the plate 11. The picker extends through an opening in the cam plate 105, which is shaped to depress the picker as it is moved in the direction of travel of the needle cylinder by engagement with the needle butts so that the needle butts are delivered to one or the other of two cams 106, which completes the depression of the needles into the active series. A spring 107 connected to the picker tends to move it up into active position with its inner end within a recess in the cover cam plate 108. The picker is moved into and held in inactive position by a pin 109 mounted to slide through the post 103 and engaging an inclined surface 110 on the picker. The lower end of the pin is engaged by a cam 111 formed on a flat cam ring 112 (Fig. 9). The cam ring is concentric with the needle cylinder and is mounted for movement in a guideway formed

within the casing 113. When the cam 111 is in position to support the pin 109 the needle depressing picker is held in lowered inactive position. When the cam is moved from under the pin the picker is released and is moved up into active position by its spring. The single acting needle raising pickers 114 are similar in construction to the needle depressing picker and their movement into or out of action is controlled in like manner by pins 75 passing through the picker posts and acted upon by cams 115 on the cam ring 112. A spring 116 is connected to the cam ring and tends to move the ring in a direction to release the pickers. The ring is moved in the opposite direction and its position is controlled by a lever 117 provided at its forward end with a pin 118 arranged to engage a finger 119 projecting from the ring. The lever is provided with an upwardly projecting cam 85 roll 120 arranged to be engaged by a cam 120' on the pattern drum (Figs. 8 and 8a). The ring is normally in position to hold all the pickers in inactive position. In going onto the heel or toe the ring is moved to throw the lifting pickers into action, and at the end of the narrowing is again moved in the same direction to throw in the depressing picker. At the completion of the heel or toe the ring is restored to normal position and throws all 95 the pickers out of active position.

The instep cam 121 for raising the long butt needles into the inactive series at the beginning of the heel or toe and for returning the inactive needles to the active series at the completion of the heel or toe is secured on the inner end of a radial shaft 122 which is mounted in a bearing bracket 123 secured to the plate 11 (Figs. 4 and 8). A coiled spring 124 within the bearing for the shaft tends to hold the cam normally in raised position. The cam is lowered into position to raise the long needle butts by a rod 125, the upper end of which is arranged to engage an arm 126 secured to the outer end of the shaft 122. The rod is forced upward by a spring 127, which is strong enough to overcome the force of spring 124. The rod is normally held in its lower position, indicated in Fig. 4, by a lever 128, the forward end of which overlies a laterally projecting pin 129 secured to the lower end of the rod and the rear end of which carries a roll 130 overlying the forward end of the lever 40 which raises and lowers the pin for shifting the motion changing clutch into engagement with the oscillating pinion. During rotary knitting the lever 40 is raised and holds the lever 128 and the rod 125 in the position indicated in Fig. 4 so that the instep cam remains in its raised position. When the lever 40 is lowered to effect the change from rotary to reciprocating in going onto the heel or toe the lever 128 and rod 125 are released and the spring 127 acts to swing the instep cam down into the position indicated 130

cated in Fig. 11 where it will engage the long butt needles and lift them into the inactive series during the forward rotation of the needle cylinder preceding its first reverse stroke. When the motion is to be changed from reciprocating to rotary at the completion of the heel or toe the lever 40 is raised and operates through the lever 128 to depress the rod 125 so that the instep cam is swung 10 up by the spring 124 into position to return all of the inactive needles to the active series.

The web holders 131 are mounted to slide radially in a dial 132 secured to the upper end of the needle cylinder and are provided with 15 butts 133 which engage a concentric groove 134 formed in a web holder cam ring 135 and are acted on by advancing and retracting cams arranged at a gap in the groove (Figs. 4, 5 and 10). The cam ring is provided with 20 two advancing cams 136 and 137 for advancing the web holders at the knitting points during rotary and reciprocatory knitting, and with two retracting cams 138 and 139 for withdrawing the web holders as they approach 25 the knitting points. The cams 138 and 139 are rigidly connected with the cams 137 and 136 and are spaced therefrom to form a guideway for the web holder butts which positively controls their movements and prevents 30 over-driving of the web holders under the action of the advancing cams. The two sets of cams are carried on the inner ends of two radially movable cam carrier levers 140 and 141 which are pivoted at 142 and 143 to 35 the web holder cam ring and are pressed radially outward by springs 144. Each set of cams is thus radially movable and its active position is determined by one of two stationary controller cams 145 and 146 adjustably 40 supported upon a fixed bracket 147. The controller cams are so arranged that when the cam ring is in position for rotary knitting the lever 140 will be in engagement with the controller cam 145 and the advancing cam 45 136 will be held in active position while the lever 141 will be pressed outward by its spring to hold the advancing cam 137 out of active position and the retracting cam 138 in position to retract the web holders preparatory 50 to their advance by the active advancing cam 136. When the cam ring is shifted on a reverse stroke of the needle cylinder in reciprocatory knitting the lever 141 will be carried into engagement with its controller cam 146, thus forcing the advancing cam 137 into active position while the lever 140 will be disengaged from its controller cam and will be moved outward by its spring to withdraw the advancing cam 136 from active 55 position and to project the retracting cam 139 into active position. The controller cams are so shaped that when the needle cylinder is raised or lowered to lengthen or shorten the stitch they will vary the radial position of the active web holder advancing 60 65

cam so that the advance movement of the web holders will be varied in accordance with the variations in the length of the stitch.

The above construction and mode of operation of the web holder actuating cams corresponds generally to that shown and described in Patents No. 1,483,904 dated February 19, 1924 and No. 1,483,905 dated February 19, 1924 issued to the present applicant.

The latch ring 148 of the machine is mounted 70 for universal adjustment in a latch ring carrier 149 which is pivoted at 150 to a supporting bracket so that the latch ring and the parts carried thereby may be swung out of and into active relation to the needles 80 (Figs. 5, 6 and 7). The latch ring is provided with a groove engaged by three studs 148' having eccentric heads fitting within holes in the carrier and clamped in adjusted position by the overlapping heads of clamping screws 149'. By turning the studs the vertical position and inclination of the ring may be adjusted. The ring is centered and held in position horizontally by three adjusting screws 150'. This construction is generally 90 the same as that shown and described in Patent No. 1,447,354 dated March 6, 1923. The latch ring is provided with an opening or throat 151 through which yarn is delivered to the needles from any one or more of a series 95 of yarn carrying fingers. In the machine shown there are six yarn carrying fingers mounted to swing about a pivot stud 152 on the latch ring carrier. Five fingers 153 are shaped to pass under a cross bar 154 on the 100 latch ring carrier and are provided with upwardly projecting arms 155 adapted to rest on a stop plate 156 on the bar and to determine the active or yarn feeding position of the fingers. The sixth finger 157 is shaped to 105 pass over the bar and to rest on the bar when the finger is in active position. This finger may be utilized to deliver yarn to the needles during any desired part of the knitting and may also be utilized to deliver a splicing yarn 110 to the needles for a part only of each course as, for instance, in high splicing above the heel or in splicing the sole of the stocking. Each finger has a rearwardly projecting arm 115 158 to which is attached a spring 159 tending to hold the finger in its active position. The fingers are swung into inactive position by a series of actuating levers 160, the upper ends of which are arranged to engage the arms 158 and the lower ends of which are pivotally supported upon a fixed stud 161. The levers are provided with contact lugs 162 arranged to ride on a series of cam rings 163 on the pattern drum. The upper ends of the actuating levers are held in alignment with the arms 158 by flanges 164 on the arms which project on opposite sides of the levers. The levers are also provided at their upper ends with segmental bearing surfaces 165 which are approximately concentric with the stud 150 and 120 125 130

which serve to support all of the fingers in raised position with relation to the throat of the latch ring when the latch ring is swung up away from the needles and thus maintain 5 the yarns leading from the fingers to the yarn clamp within the latch ring in proper separated relation while the latch ring is raised. The spring 159 for the finger 157 is connected directly to the corresponding arm 158 while 10 the springs for the other yarn-carrying fingers are connected to the respective arms 158 by links 166 which embrace the arms and have their forward ends seated within notches 167 in the arms (Fig. 6). 15 The mechanism for operating the yarn finger 157 to deliver its yarn to a part only of the needles during each revolution of the needle cylinder, as in high splicing above the heel, or in reinforcing the sole, comprises a 20 second actuating lever 168 arranged at the side of the lever 160 and corresponding thereto in shape. This lever is provided with an arm 169 extending beyond the pivot stud 161 and arranged to be engaged by a cam 170 25 on a slide 171 which is mounted to move radially of the needle cylinder (Figs. 5 and 9). The slide is forced forward by a spring 172 and its forward end is provided with two bearing surfaces 173 and 174 arranged one 30 above the other and at different distances from the center of the needle cylinder. The bearing surface 173 is arranged to ride on the periphery of a vertical cam rib 175 formed on the cylinder gear 3 and the bearing surface 174 is arranged to ride on adjustable wing cams 176 secured at each end of the high part 177 of the cam rib. The wing cams may be adjusted circumferentially to determine the points at which the cam slide 35 171 is advanced and retracted. The cam slide is normally held in inactive position out of engagement with the cams on the needle cylinder gear by a controlling lever 178, the forward end of which is provided 40 with a cam surface 179 adapted to engage a shoulder 180 on the cam slide and the rear end of which rides on a cam rib 180' on the pattern drum. When the controller lever is 45 on the high part of the cam rib the cam slide 171 is held in retracted position with the arm 169 of the lever 168 in front of the cam 170. The lever 168 is, therefore, in retracted or inactive position. When the controller lever 178 rides onto the low part of the cam 50 rib the cam slide 171 is released and moves forward into engagement with the cam rib on the needle cylinder gear, the cam 170 passing to a position directly in front of the lower end of the lever 168. Now during each 55 revolution of the needle cylinder the cam slide is pushed back as the bearing surface 174 rides onto one of the wing cams and is retained in its rearward position by this cam or by the engagement of the surface 173 with 60 the high part 177 of the cam rib until the 65

surface 174 rides onto and then off of the other wing. The cam slide is then retained in its forward position by the engagement of the surface 173 with the low part 175 of the rib cam until it is again retracted by the wing 70 cam. The cam slide is thus advanced and retracted at definite points in each rotation of the needle cylinder determined by the adjustment of the wing cams. Each time the cam slide is retracted the cam 170 thereon 75 swings the lever 168 in a direction to raise the yarn carrier finger 157, and each time the cam slide advances the cam 170 withdraws from the lever and allows the finger to move into active position. The finger 80 157 thus inserts and withdraws its yarn during each revolution of the needle cylinder so long as the cam slide 171 is in action. When the cam slide is withdrawn and retained in inactive position by the controlling lever 178 85 the movement of the finger 157 into or out of active operation is controlled by its actuating lever 160.

Whenever the yarn finger 157 is operated at each revolution of the needle cylinder to 90 insert and withdraw a re-inforcing yarn the stitch should be lengthened or loosened while the finger is active and should be shortened or tightened while the finger is out of action during each revolution of the needle cylinder. To thus loosen and tighten the stitch the needle cylinder is raised at the point in its revolution where the yarn finger 157 is rendered active and is lowered at the point where the finger is rendered inactive. The 95 mechanism for raising and lowering the cylinder during each revolution comprises a cam 181 carried by the gear 22, which makes one revolution for each revolution of the needle cylinder and an arm 182 secured to the rod 100 14 and carrying an adjustable contact piece 183 which may be moved into and out of the path of the cam through connections leading to the pattern drum. The cam 181 in the form shown comprises two superimposed eccentric disks which are adjustably secured to the gear 22 by screws 184 and which may be adjusted relative to each other to vary the contour of the cam and thus determine the points at which the needle cylinder will be 105 raised and lowered. A spring 185 is connected to the hub of the arm 182 and tends to swing the arm out of the path of the cam and thus render the needle raising and lowering mechanism inactive. The arm is swung 110 into the path of the cam and retained in active position through a bell crank lever 186, one arm of which is connected through a link 187 with an arm depending from the hub of the cam arm 182 and the other end of which is engaged by the lower end of a vertical pin 188, the upper end of which is arranged in the path of the cam 188' on the pattern drum (Figs. 4, 8^a and 9). When the arm 182 is in active position the cam 181 115 120 125 130

advances and retracts the rod 14 during each revolution of the needle cylinder and thus oscillates the worm ring 4 to raise and lower the needle cylinder and thus tighten 5 and loosen the stitch.

Whenever the yarn is withdrawn by raising one of the yarn fingers 153 into its upper inactive position or whenever the yarn finger 157 is raised into a similar inactive position by its controlling cam on the pattern drum the yarn thus withdrawn from the needles is severed and held by yarn severing and clamping mechanism carried upon the latch ring carrier. This mechanism comprises two yarn holding clamps 189 and 190 mounted upon a plate 191 and a yarn severing hammer 192 cooperating with an anvil 193 on the plate (Figs. 5, 6 and 7). The two clamps are similar in construction and mode 20 of operation to the clamps shown and described in Patent No. 1,352,079, September 7, 1920. The clamp 190 is pivoted to a support 194 rising from the plate 191 and the rear end of the clamp is engaged by the lower 25 end of a pin 195, the upper end of which is acted upon by a cam 196 secured to the under side of an actuating slide 197 and acting to depress the pin and thus open the clamp. The clamp 189 is pivoted on a transversely 30 movable slide 198 which is drawn forward by a spring 199 and is retracted through a lever 200 carrying a vertically projecting pin 201 arranged to be acted upon by a switch cam 202 carried by the slide 197. When the slide 35 is retracted a pin 203 projecting laterally from the clamp 189 passes under a yielding switch cam 204 so that the clamp remains closed during its rearward movement. When the clamp slide moves forward the pin 203 40 rides up over the switch cam 204 thus opening the clamp so that it passes over the withdrawn yarn and as the clamp slide completes its forward movement the pin drops off the forward end of the switch cam 204 so that 45 the clamp closes and holds the yarn until it is again retracted upon the withdrawing of another yarn. While the clamp 190 is 50 withdrawn and advanced to receive and clamp the withdrawn yarn the clamp 190 is closed so that the yarns are at all times held by one or both of the clamps.

The yarn-breaking hammer 192 is carried on the end of a lever 205 and is normally held in engagement with the anvil 193 by a spring 206. The hammer lever is raised and dropped to strike a blow upon the anvil 193 by a cam 207 secured on the upper side of the slide 197 and arranged to ride under a pin 208 which is mounted in the lever 205 and is yieldingly supported by a spring 209 so that it may 65 yield to allow the passage of the cam during

the return movement of the cam 207. The slide 197 may carry two or more cams 207 so that the hammer may strike repeated blows upon the anvil whenever a yarn is withdrawn and is to be severed.

Whenever a yarn is withdrawn the travel of the needles carries it over the plate 191 and under the clamp 190 and hammer 192 which have been opened to receive it. In order that the withdrawn yarn may be uniformly and accurately positioned above the plate 191, with relation to the clamps and severing device, a transverse guide plate 210 is arranged above the plate 191 in front of the clamp 189 and acts to guide the yarn leading from the raised yarn finger to the knit fabric into position close to the upper side of the clamp 189. To insure the passage of the yarn under the guide plate the plate is provided with a forwardly projecting finger 211 which extends 85 into a position closely adjacent to the inner side of the needle series and catches the yarn, thus preventing its passage over the end of the guide plate. The outer end of the guide plate is preferably provided with an inwardly and rearwardly extending projection 212, the under edge of which is inclined and tends to deflect any projecting fabric down under the end of the guard during the reverse stroke of the needle cylinder in knitting the heel or toe.

The mechanism for advancing and retracting the slide 197 to operate the yarn clamps and thread severing hammer comprises a spring 213; Fig. 4, which holds the slide in 100 retracted position and a lever 214 mounted on a fixed pivot and provided with a cam surface engaging the rear end of the slide. The mechanism for rocking the lever to advance and retract the slide comprises a cam 215 105 secured to the rotary pinion 29 and therefore rotating in time with the needle cylinder (Figs. 5, 14, and 15). The connections between the cam and lever are normally inactive and are rendered active when the yarn 110 severing and clamping devices are to be operated by a cam on the pattern drum. These connections comprise a lever 216 engaging the cam 215 and provided with a hub 217 carrying a forwardly projecting arm 218 arranged 115 to underlie the lower end of a vertical rod 219. The upper end of the rod carries a collar 220 provided with a laterally projecting pin 221 and the rod is held normally in its raised position by a latch 222 which is mounted 120 upon a fixed pivot and engages the pin. The latch is held yieldingly in engagement with the pin by a spring 223 (Figs. 4, 5 and 6). The latch is disengaged from the pin by a finger 224 on the lower end of a swinging 125 arm 225 which is arranged to engage a pin 226 on the latch. The arm 225 also carries a coupling rod 227 which is brought into position between the collar 220 on the rod 219 and the horizontal arm of the lever 214 when 130

the latch is disengaged from the pin 221 and the rod 219 moves down to its lowest position. This coupling rod is mounted to slide in a bearing sleeve 228 which is pivotally supported on the arm 225 and is held yieldingly in position with a pin 229 in engagement with a stop finger 230 on the arm by a spring 231. The arm is swung about its pivot by a lever 232 having an arm arranged to be engaged 10 by a series of pins 232' projecting from the cam disk 43 of the pattern drum.

When a yarn is withdrawn the movement of the pattern drum which operates a yarn carrier finger to withdraw its yarn also causes 15 a pin 232' to operate the lever 232 and swing the arm 225 toward the left in Fig. 4. This movement of the arm disengages the latch 222 from the pin 221 and also carries the pivot for the bearing 228 into vertical alinement 20 with the rod 219, the spring 231 yielding in case the rod 227 is carried against the collar on the upper end of the rod 219. The disengagement of the latch releases the rod 219 so that it is free to move downward as the 25 cam lever 216 rides onto the low part of the cam 215. When the rod moves downward the coupling rod 227 swings into position above the upper end of the rod so that it will be raised by the rod 219 when the lever 216 30 rides up onto the high part of the cam 215 and will rock the lever 214 to advance the slide 197. Meanwhile, the pin 232' on the pattern drum has released the cam lever 232 so that the arm 225 and latch 22 are free 35 to return to normal position as the rod 219 completes its upward movement, thus releasing the lever 214 and re-engaging the latch with the pin at the upper end of the rod 219. The yarn is usually changed at the beginning 40 of reciprocatory knitting in going onto the heel or toe and the yarn severing device should at this time be operated to sever the yarn as the needle cylinder and the oscillating segment are nearing the end of their forward stroke, since at this point in the travel 45 of the needle cylinder the yarn is properly positioned with relation to the severing device. The cam 215 is, therefore, so timed that the yarn severing hammer will act upon the yarn 50 when the oscillating segment and needle cylinder have nearly reached the end of their forward stroke and are about to be reversed.

It is sometimes desirable to provide a knit fabric with anti-run-back courses at one or 55 more points, for instance, in knitting ladies' stockings, an anti-run-back course is frequently introduced to arrest or prevent running in case of broken stitches in the garter top. The present machine is accordingly 60 provided with mechanism for inserting anti-run-back courses at any desired points and this mechanism is adapted to knit the form of anti-run-back courses shown and described in Patent No. 1,333,763, Mar. 16, 1920. In 65 knitting this form of fabric a supplemental

yarn is fed to alternate needles to be knit in with the main yarn for one or more courses. In order that the yarn may be thus fed means is provided for pressing forward alternate needles into such position that they will fail 70 to take the yarn delivered by the yarn changing finger which carries the supplemental yarn. As shown this means comprises a series of radially sliding pins 233 mounted in the upper end of the needle cylinder back of 75 alternate needles and provided with enlarged heads engaging the backs of the needles (Figs. 5 and 6). The inner ends of these pins project into the path of a cam 234 which is mounted in a sleeve 235 supported within the 80 needle cylinder by pins 236 which project through the sleeve into an annular groove in the interior of the needle cylinder. The cam 234 is normally in retracted inactive position and is projected into active position at the 85 proper intervals by a wedge-shaped cam slide 237 pivoted to the upper end of a slide bar 238, the lower end of which is engaged by one arm of a bell crank lever 239 (Fig. 2). The other end of the bell crank lever is connected 90 by a link 240 with the lower end of a lever 241. The upper end of the lever is arranged to be engaged by a cam on the pattern drum which operates through the connections described to project the cam 234 into active 95 position for one or more revolutions of the needle cylinder and then release it so that it may return to normal retracted position under the influence of the needles. The slide 238 is held in retracted position by a spring 100 242. In order that the extent to which the needles are bent forward may be accurately adjusted the cam slide 237 rests against the front face of an adjusting lever 243. The position of the adjusting lever is regulated 105 by a vertically movable slide 244, the upper end of which rests against the cam surface on the lower end of the lever and the lower end of which rests on the head of a vertically adjustable screw 245. The lever 243 is mounted upon a fabric guiding tube 246 arranged within the cam carrying sleeve 235 and mounted in the upper end of a cylinder 247 which is in turn secured within a supporting 110 ring 248 attached to the casing 113. The slides 238 and 244 are mounted within the cylinder 247 and the sleeve 235 is held from rotation by a pin 247' connecting it to the tube 246.

When the cam 234 is projected into active 120 position every alternate needle is bent forward as it comes to the point at which the supplemental yarn is delivered, so that this yarn passes back of these needles and is delivered only to the un-deflected needles. In 125 order to thus feed the yarn the yarn finger 153 which carries the supplemental yarn is first lowered to carry its yarn between two adjacent needles and then after several needles have taken yarn, the yarn guide is raised to a 130

point where the yarn eye is just above the tops of the needles and in position for its yarn to pass down back of the deflected needles and in front of the un-deflected needles. The main 5 yarn being delivered at a lower and later point is taken by the deflected as well as the un-deflected needles. The supplemental yarn is, therefore, knit in with the main yarn on alternate needles only, and thereby forms the 10 anti-run-back course of the patent above referred to. To maintain the un-deflected needles in proper position in the needle grooves when the alternate needles are pressed forward, retaining pieces 249 are arranged in the 15 needle grooves in front of the un-deflected needles and are pressed against the fronts of the needles by an encircling coil spring 250.

In knitting half hose the needles are automatically leveled substantially at the knock-over level after the completed stocking has 20 been run off and before the machine is automatically stopped. For this purpose the cylinder 93, which surrounds the needle cylinder and carries the knitting cams, is provided 25 with a groove 251 for the butts of the leveled needles and the side cam 97 is so mounted that it may be moved radially out of the path of the needle butts to permit the needles to be leveled by the rotary stitch cam 95 (Figs. 8, 30 11, 12 and 13). A supplemental leveling cam 252 is also provided which is moved radially inward to depress those needles which are passing up the cam 97 when it is withdrawn. The support 253 which underlies the needle 35 butts as they approach the picker 114 on the reverse stroke in reciprocatory knitting is also mounted to move radially to allow the passage of any needle butts which are on the cam 97 when it is withdrawn. The side cam 40 97 is secured on the forward end of a radially movable slide 254 and is automatically withdrawn when the needles are to be leveled by a lever 255, one end of which engages a pin on the slide and the other end of which is engaged by the forward end of a rod 256 (Figs. 2 and 8). The rear end of the rod is engaged 45 by a lever 257 which is in turn engaged and actuated by a cam 257' on the pattern drum. The slide is forced forward by a spring 258 (Fig. 13). The cam 252 is carried on the end of a lever 259 and is forced yieldingly forward by a spring 260 connected to the lever. The cam is retracted when the side cam moves 50 forward into active position by a pin 261 on the slide 254 which engages the end of the lever 259. The support 253 is carried on the end of a lever 262 and is held yieldingly in active position by a spring 263 connected to the lever. The side cam 98 is normally in position to cross the leveling groove 251 and is mounted to yield radially to permit the passage of the needle butts travelling along the groove. For this purpose the cam is formed 55 on the end of a lever 264, pivoted at 265, and held yieldingly in forward position by a 60 spring pressed plunger 266.

When the needles are to be leveled the completed stocking is run off and the latch ring is raised sufficiently to clear the latches on the needles. The latch ring is thus raised by the 65 advance movement of the pattern drum shaft which withdraws the knitting yarn and throws into operation the yarn severing and clamping mechanism. The means for lifting the latch ring consists of a lever 267 pivoted on the stud 150 and provided at its forward end with lateral projections underlying the latch ring carrier (Figs. 4 and 5). The lower end of the lever is acted on by a cam 267' 70 on the pattern drum. After the latch ring is 75 raised the pattern drum shaft is again advanced and retracts the side cam 97 at the point in the rotation of the needle cylinder when the first of the series of long butt needles are passing up the cam as indicated in Fig. 85 12. The withdrawal of the side cam permits the cam 252 to move forward so that it rests against the ends of the short butts and is in position to engage and deflect the long butts which were passing up the cam 97 and to direct 90 these needles down onto the incline 268 which completes their movement into the leveling groove 251. The remaining long butt needles and all the short butt needles are directed down into the leveling groove by the 95 stitch cam 95 so that at the completion of a revolution of the needle cylinder all the needles will have been brought to the knock-over level with the upper ends below the tops of the web holders. The needles having been 100 leveled the machine automatically stops. The operator then swings the latch ring up out of the way and applies the transfer quill cup to the web holders. Then the needles are projected into the quills by lowering the needle cylinder. To permit the abnormal rotation of the worm ring 4 requisite for projecting the needles up into the quills the cam disk 19 which engages the contact piece 18 on the 105 end of the lever 17 is provided with a deep depression 19' which registers with the end of the lever when the machine is stopped (Figs. 4 and 8). To permit the contact piece to enter this recess the cams which register with the contact piece 20 at this time when knitting fashioned stockings are removed when knitting half hose. The rotation of the worm ring in a direction to lower the cylinder is at this time limited by a latch 269 mounted on the outside of the casing 113 and 110 provided with a stop shoulder 270 adapted to engage an arm 271 which projects from the worm ring through a slot 272 in the casing. The latch is held in engagement with the under side of the arm by a spring 273. After 115 the quill cup has been applied to the web holders the latch 269 is depressed by the operator, thus freeing the worm ring so that it 120 125

is moved by its spring in a direction to lower the cylinder until the arm 271 brings up against the end of the slot 272. This projects the needles up above the web holders and into 5 position to receive the loops carried by the transfer quill cup.

After the loops have been transferred the latch ring is swung down into position and the machine started. The pattern drum shaft 10 is immediately advanced and a cam 18' on the disk 19 acts on the contact piece 18 of the lever 17 and turns the worm ring to lift the needle cylinder into such position that the web holders are slightly above the tops of the needles. 15 The worm ring rests here during one or two revolutions of the needle cylinder so that the stitches carried by the needles are brought under the nibs of the web holders by the withdrawal and advance of the web holders during such revolutions. The continued movement 20 of the pattern drum shaft then causes the cam 18' to further rotate the worm ring and lift the needle cylinder to knitting position. In order that the position of the web 25 holders with relation to the tops of the leveled needles may be varied in accordance with the character of the yarn used and work being done the cam 18' is so mounted that it may be adjusted to vary its lifting effect on the needle 30 cylinder. As shown the cam is in the form of a plate pivoted at 20' on the disk 19 so that it may be moved radially. The inner edge of the plate rests on a conical surface formed on an adjusting screw 21'. By turning the 35 screw the conical surface may be advanced or retracted to vary the radial position of the cam plate. After the needle cylinder has been raised to knitting position the drum shaft is given another advance movement to release 40 the side cam slide 254 and also drop into active position one of the yarn carrier fingers. The side cam slide is released when the short butts are passing the cam so that it is forced inward by its spring and rides against the 45 short butt needles. This movement of the cam slide also withdraws the cam 252. Since the side cam 97 rides against the ends of the short butts it is in position to engage and raise the long butts to the tuck level. After the 50 short butts have passed the cam moves forward into normal position where it will act on both the long and short butts. As the needles approach the side cam 97 they are pressed back in the needle groove so that none of the 55 short butts will project far enough to ride up the cam by a spring pressed finger 274 which is mounted to swing radially and is pressed inward by a spring 275 (Figs. 11 and 12). The needles are thus returned to the active 60 level and pass through the knitting cams, the needles at the forward end of the long butt series being the first to be raised and the first to pass through the knitting cams. The knitting will, therefore, begin on the first long 65 butt needle.

When the latch ring is raised preparatory to leveling the needles and when it is swung up out of the way by the operator it is retained in each position by a spring pressed latch pin 276 arranged to engage notches 277 70 formed in a plate 278 which is secured to one side of the latch ring carrier (Figs. 2 and 7).

The knitted fabric passes down through the interior of the needle cylinder and is received within a fabric can 279 mounted upon 75 the upper end of a vertical shaft 280 (Figs. 1, 15 and 16). The shaft is rotated in unison with, but independently of, the needle cylinder and is provided with a horizontal clutch disk 281, engaged by the toothed lower edge 80 of an annular rib 282 on the bottom of the can. The shaft 280 is driven from the crank gear 34 through a beveled gear 283, which engages a pinion 284 on the upper end of a vertical shaft 285, the lower end of which is connected through beveled gears 286 with the rear end of a horizontal shaft 287. The forward end of the shaft is connected through beveled gears 288 with the lower end of the shaft 280. The gearing is so proportioned 85 that the shaft 80 rotates in unison with the needle cylinder, making one revolution for each revolution of the needle cylinder.

During rotary knitting the rib on the bottom of the fabric can rests on the disk 281 95 and the can rotates with the shaft 280. When the motion is changed from rotary to reciprocating the can is raised, thus disconnecting it from the disk 281 and shaft 280 so that it remains stationary during the oscillation of 100 the needle cylinder. Upon the change back to rotary the can is again connected with the rotary shaft 280 and is again rotated in unison with the needle cylinder. The means for raising and lowering the can to disconnect it 105 from and connect it with the shaft 280 comprises an annular support 289 underlying the bottom of the can and pivotally supported on a yoke 290 at the forward end of a lever 292. The rear end of the lever is engaged by a 110 collar on a vertical rod 293, the upper end of which is arranged to be engaged by a lever 294 which in turn is engaged and actuated by cams 295 on the pattern drum shaft. The support 289 is held yieldingly in position by supporting springs 296 and is provided with anti-friction material 297 so that it acts as a brake for stopping rotation of the can when it is lifted, as well as a support for holding it out of engagement with the clutch on the shaft 115 280.

To enable the cams of the pattern mechanism to be accurately and conveniently positioned with relation to each other and with relation to the actuating mechanism, and 120 also to enable certain of the cams to be readily replaced in adapting the machine for different kinds of work the cams carried by the pattern drum are made in the form of disks definitely located thereon and with re- 125 130

lation to each other by a key and keyway or by other means which determines the circumferential position of each disk on the drum. The cams which usually require adjustment 5 or refitting in setting up a machine for a certain kind of work or in changing from one kind to another are preferably in the form of thin metal disks which may be stamped from sheet metal and to enable each disk to 10 be readily removed or replaced by one having a different contour the disks are split or made in two half sections.

As shown in Fig. 8^a the pattern drum 298 is secured to the shaft 21 by a pin 299 and 15 is provided with a keyway 300 for circumferentially positioning the cam disks and with a flange 301 against which the assembled cam disks are held by a nut 302. The cam disks 43 for operating the clutch controlling pins 20 are comparatively thick one-piece disks and the outer disk is recessed to receive the flange 301. The cam disk 120' is also a comparatively thick one-piece disk. The intermediate disks are thin sheet metal disks and are split 25 or formed in two half sections as indicated in Fig. 5 so that any disk may be removed and replaced without removing others and without disturbing the drum and its shaft. The sheet metal disks are separated by separator disks 303. The cam disks are provided 30 with keys fitting within the keyway 300 and accurately positioning the disks circumferentially on the drum. The assembled disks are bound together and held in axial position on 35 the drum by nut 302 and flange 301 between which they are clamped by tightening the nut.

Over-running of the cam shaft under the influence of its actuating pawl is prevented 40 by a friction spring 304 which is forced against a friction washer 305 within the end of the drum by a washer 306 and nut 307. The spring and the washer 306 are held 45 against rotation by a pin 308.

The driving mechanism shown and described is claimed in the applicant's Patent No. 1,616,633, dated February 8, 1927, the transfer mechanism is claimed in the applicant's Patent No. 1,496,860, dated June 10, 50 1924, the pattern mechanism is claimed in the applicant's Patent No. 1,519,384, dated December 16, 1924, the fabric receiver is claimed in the applicant's Patent No. 1,509,871, dated September 30, 1924, and the web holder mechanism is claimed in the applicant's Patent 55 No. 1,507,022, dated September 2, 1924, each of these patents being a division of the present application.

What is claimed is:

60 1. A knitting machine having; in combination, a needle cylinder, a latch ring carrier mounted to swing up away from the needle cylinder, a series of yarn carrying fingers mounted on the carrier, and a series of actuators independently mounted and provided

with segmental bearing surfaces for maintaining the fingers in inactive position when the latch ring is swung up.

2. A knitting machine having, in combination, a needle cylinder, a latch ring carrier 70 mounted to swing up away from the needle cylinder, a series of yarn carrying fingers mounted on the carrier, a series of actuators independently mounted and provided with segmental bearing surfaces for maintaining 75 the fingers in inactive position when the latch ring is swung up, and a yarn clamp mounted on the carrier and arranged within the latch ring.

3. A knitting machine having, in combination, a rotary needle cylinder, a latch ring carrier, a yarn carrying finger mounted on the carrier, an actuating lever therefor mounted independently of the carrier, a slide provided with a cam for oscillating the lever, 85 a cam rotating in time with the needle cylinder for reciprocating the slide, and means for rendering the first named cam active or inactive.

4. A knitting machine having, in combination, a rotary needle cylinder, a latch ring carrier, a yarn carrying finger mounted on the carrier, an actuating lever therefor mounted independently of the carrier, a slide provided with a cam for oscillating the lever, 90 a cam rotating in time with the needle cylinder for reciprocating the slide and a pattern mechanism for controlling the engagement of the slide with the cam.

5. A knitting machine having, in combination, a rotary needle cylinder, a yarn finger, means for moving the yarn finger into and out of action during each revolution of the needle cylinder, a worm ring for supporting the needle cylinder, and mechanism for oscillating the ring to raise and lower the needle cylinder in time with the movement of the finger into and out of action. 105

6. A knitting machine having, in combination, a rotary needle cylinder, a yarn finger, 110 means for moving the finger into and out of action during each rotation of the needle cylinder, a worm ring for supporting the needle cylinder, a cam rotating in time with the needle cylinder, and connections between 115 the cam and worm ring for oscillating the ring movable into and out of active relation to the cam.

7. A knitting machine having, in combination, a needle cylinder, motion changing mechanism for rotating and for oscillating the needle cylinder, a series of yarn changing fingers for presenting a plurality of yarns to and withdrawing them from the needles, common means for severing and holding the withdrawn yarns and a cam on a continuously moving part of the motion changing mechanism for operating the yarn severing and holding means. 120

8. A knitting machine having, in combina- 125

tion, a needle cylinder, motion changing mechanism for rotating and for oscillating the cylinder, yarn changing fingers, common means within the needles for severing and holding the withdrawn yarns, actuating mechanism for the yarn severing and holding means, comprising a cam on a continuously moving part of the motion changing mechanism, and pattern mechanism for controlling the action of the cam.

9. A knitting machine having, in combination, a rotary needle cylinder, motion changing mechanism for rotating and oscillating the cylinder, yarn changing fingers for presenting yarns to and withdrawing them from the needles, a cam on a continuously moving part of the motion changing mechanism, common yarn severing and holding means operated by the cam, and means for rendering the cam active to effect a single actuation of the severing and holding means when a yarn is withdrawn.

10. A knitting machine having, in combination, a rotary needle cylinder, a pivoted latch ring carrier, yarn changing fingers on the carrier, yarn severing and holding means on the carrier within the needles, an actuating slide on the carrier, a continually rotating cam, normally inactive connections for transmitting motion from the cam to the actuator slide, and pattern mechanism for rendering the connection active to effect a single actuation of the slide when a yarn is withdrawn.

11. A knitting machine having, in combination, a needle cylinder, mechanism for rotating and for oscillating the cylinder, a pivoted latch ring carrier, yarn changer fingers on the carrier, a pattern mechanism for operating the fingers, yarn severing and clamping means on the carrier within the needles, an actuator slide therefor on the carrier, a cam rotated by the needle cylinder rotating mechanism, normally inactive connections for transmitting motion from the cam to the actuator slide, and means controlled by the pattern mechanism for rendering the connections active to transmit a single actuating impulse to the slide.

12. A knitting machine having, in combination, a needle cylinder, yarn changing fin-

gers, a plate within the needles, yarn clamping means on the plate, a separate transverse guide above and parallel to the plate to guide the withdrawn yarns over the plate, and a forwardly projecting finger on the guide for catching the yarn and preventing its passage over the end of the guide.

13. A knitting machine having, in combination, a needle cylinder, yarn changing fingers, a plate within the needles, yarn clamping means on the plate, a separate transverse guide plate above the plate in front of the clamping means, and a yarn catching finger projecting forward from the guide plate into position close to the needles.

14. A knitting machine having, in combination, a needle cylinder, yarn changing fingers, a plate within the needles, yarn clamping means on the plate, a transverse guide plate above the plate in front of the clamping means, a yarn catching finger projecting forward from the guide plate into position close to the needles, and an inwardly and rearwardly extending connection on the end of the guide plate the under edge of which is inclined.

15. A knitting machine having, in combination, a needle cylinder, means for feeding a main knitting yarn to all of the needles, means for pressing forward alternate needles, a supplemental yarn carrier, means for positioning said carrier to deliver its yarn to the un-deflected needles only to be knit in thereby with the main yarn, and pattern mechanism to actuate the carrier to insert and withdraw its yarn and to render the pressing means active and inactive.

16. A knitting machine having, in combination, a needle cylinder, means for feeding a main knitting yarn to all of the needles, means for pressing forward alternate needles, a supplemental yarn carrier, means for lowering the carrier to insert its yarn between adjacent needles and for immediately thereafter raising it into position for its yarn to pass down back of the deflected needles and in front of the undeflected needles to be taken and knit in thereby.

MAX C. MILLER.
